Christian Bitzer Inventor

By his Attorney George C. Heinrich

UNITED STATES PATENT OFFICE.

CHRISTIAN BITZER, OF NEW YORK, N. Y.

SEWING-TABLE ATTACHMENT.

Application filed February 3, 1926. Serial No. 85,690.

This invention relates to improvements in attachments for sewing tables, sewing machines or the like, and it is the principal object of the invention to provide an attachment which can be readily set up for use as a receptacle for the various paraphernalia used when sewing, and which can be conveniently folded against the table or machine frame when not in use.

Another object of the invention is the provision of a sewing table or machine attachment comprising a substantially box-shaped, collapsible receptacle adapted to be attached by simple means to the side of a sewing table or machine frame, and to be supported by a bracket or the like.

A further object of the invention is the provision of a sewing table or machine attachment having its sides and end walls, as well as the bottom thereof hingedly attached to each other to allow a folding of the box into a comparatively small compass.

A still further object of the invention is the provision of an attachment for sewing machines and sewing tables of simple and inexpensive construction, yet durable and efficient.

These and other objects and advantages of my invention will become more fully known as the description thereof proceeds, and will then be more specifically defined in the appended claim.

In the accompanying drawing forming a material part of this disclosure:

Fig. 1 is a fragmentary front elevation of a sewing machine equipped with an attachment constructed according to my invention in operative position.

Fig. 2 is a similar view, with the attachment folded.

Fig. 3 is a top plan view of the attachment box.

Fig. 4 is a section on line 4—4 of Figure 1.

A sewing machine table 10 of any well known type and construction, carrying the machine 11 etc., has attached to the outer face of one of its side walls or frame bars 12 a bracket 13 into which fits the lower end of a bar 14, removably or stationary, the upper end of which is secured, removably or not, to the end wall 15 of a folding box having its side walls hinged, as at 16 and 17 respectively,

to the end walls, while the bottom plate 18 is hingedly attached, as at 19, to the end wall 15.

A bracket 20 is attached to the box bottom 18 and has removably secured thereto, by means of a pin or the like, the upper end of an arm 21, the lower end of which is pivotally attached, as at 22, to the outer face of bar 12, or an ear secured thereto.

The operation of my device will be entirely clear from the above description when considered on hand of the drawing, if it is desired to use the box, the arm 21, which normally has the position shown in Figure 2, is raised and connected with its upper end to the bracket 20, the box is unfolded and set up as indicated for the reception of yarn spools, scissors, or sewing material and other sewing paraphernalia or accessories, which are then handy to the user or operator of the machine and will not in any way hinder the operation of the machine or form an obstruction on the sewing table.

It is to be understood, that I have shown and described as an example the preferred form of my device, and that such changes as come within the scope of the appended claim can be made without deviation from the principles involved.

Having thus described my invention, what I claim as new and desire to secure by Letters Patent is:

In combination with a table provided at its side with a pleat bracket and a stop pin spaced vertically from each other, a box attachment comprising side and end panels hingedly connected together, a bottom panel hingedly connected with one of the end panels, a bar attached to the said end panel and adapted to enter the pleat bracket, a prop arm pivotally connected with the bottom panel approximately at the center thereof, and adapted to engage the stop pin to hold the bottom panel at a horizontal position, said bottom panel adapted to be swung from a horizontal position to a vertical position, and cover the bracket and the stop pin of the table.

Signed at New York, in the county of New York and State of New York, this 23rd day of January, A. D. 1926.

CHRISTIAN BITZER.
